BOILER WATER RECLAMING DEVICE

Earl D. Hall, Meadville, Pa., and Harold D. Barber, Shaker Heights, Ohio

Application March 19, 1947, Serial No. 735,678

1 Claim. (Cl. 210—52)

1 Our invention relates to means for reclaiming steam boiler water laden with suspended matter, by removing such matter therefrom and returning the cleansed water to a storage tank for reuse in the boiler.

It is one of the objects of the invention to provide means of this character in which baffles, moving parts and/or filters are eliminated, thus dispensing with the necessity of replacement of such parts due to wear, corrosion or clogging.

Another object of the invention is the provision of an apparatus of the class described which is particularly effective in connection with removing suspended matter from water used in locomotive boilers, thus permitting the cleansed water to be redeposited in the water supply tank of the tender for reuse as contrasted with the custom of discharging the laden water from the boiler and along the right of way. Such practice not only requires more frequent renewal of the water supply, but is destructive to the ties along the right of way.

Another object of the invention is the separation of suspended matter, such as, boiler sludge, mud, etc. from steam boiler water by delivering the laden boiler water to a separation tank, maintaining the tank filled with the water and excluding air therefrom, and allowing the suspended matter to settle into a sump or the like for subsequent removal as the water passes through the tank.

A further object of the invention is to prevent agitation of the laden water in the separation tank without resorting to the use of baffles or other similar means, whereby the separation of sludge from the water may be carried out efficiently and effectively even though the tank may be subjected to vibration or movement as, for instance, when the invention is used in connection with locomotive boiler water systems. In such use the tank may be carried in the tender.

A still further object of the invention is the provision of an apparatus of this character which is extremely simple in construction, effective and efficient in operation, and which can be built, installed, and operated at extremely low cost.

Other objects and advantages of our invention will become more apparent as the following description of an embodiment thereof progresses, reference being made to the accompanying drawing in which like reference characters are employed to designate like parts throughout the same.

In the drawings:

Figure 1 is a top plan view of an apparatus em-

bodying our invention and shows the same applied in use on a locomotive tender.

Figure 2 is a vertical section of the same taken on line 2—2 of Figure 1.

Figure 3 is a horizontal section through the steam separator taken on line 3—3 of Figure 2, and,

Figure 4 is a transverse section through the steam separator taken on line 4—4 of Figure 3.

10 While we have illustrated the invention as used in connection with locomotive boilers, it will be understood that we do not intend to limit the same in this respect, since it is equally well adapted to use with stationary boiler or other 15 systems where it is desirable to remove suspended matter from a laden fluid and to reuse or recirculate the unladen fluid in such systems.

In carrying out our invention as applied to 20 locomotive boilers, the water taken from the boiler and usually laden with scale, sludge, mud or other suspended matter is conveyed from the boiler either through a blow-off device (not shown) or other suitable connection through a pipe 1, and is delivered substantially tangentially 25 to the upper part of a centrifugal steam separator 2 in the tender 3 supported in an elevated position over the settling tank 4 by means of support 5.

The centrifugal separator comprises a cylindrical body 2 provided with a domed top 6 and is open to the outside atmosphere through the opening 7. A plurality of plates concentrically arranged as at 8 and 9, and having oppositely disposed openings 10, depend from the top 6 within the body to within a short distance of the bottom wall or floor 11 of the separator, while an outlet or discharge pipe 12 communicates with the interior of the separator near its lower wall 11 and with a distributing manifold 13 within one end of the settling tank 4.

It will be understood that when water laden with suspended matter is delivered from the boiler to the steam separator, it is substantially at boiler pressure. Since the steam separator is open to atmospheric pressure through the opening 7, the incoming water will be subjected to a pressure drop, thereby releasing steam and heat which is vented through the opening 7 to the outside atmosphere. Water at boiler pressure or thereabouts entering the steam separator will be whirled within the separator 2 and between the plates 8 and 9 and, as explained above, will be subjected to a pressure drop before it flows at atmospheric pressure out through the discharge pipe 12 and into the manifold 13.

The manifold 13 is supported within the settling tank 4 and is preferably located at one end thereof and just below the inclined top wall 14 of the tank as shown in Figure 2. The manifold is provided with a plurality of perforations or holes 15 spaced at intervals to distribute the flow of laden boiler water across the width of the tank. It will be noted that the top wall 14 of the tank is inclined upwardly and outwardly from its left hand end as in Figure 2, and terminates in a plurality of openings 16 at the other end of the tank. Mounted above the settling tank, but below the level of the steam separator, is a reserve storage tank 17 having a plurality of openings 18 in its bottom wall communicating with the openings 16 of the settling tank to first permit the escape of all air from the tank 4 as the water level therein rises and then to conduct water from the tank 4 to the reserve tank 17. Since the top wall 14 is inclined upwardly it will be impossible to trap any air in the tank 4, since as the water level rises to the top wall all remaining air in the tank will be exhausted through the openings 16 and 18. Thus, when the tank 4 becomes completely filled with particle laden boiler water 25 agitation of the water body therein will be prevented even as a result of tank vibration or movement under running conditions. The body of water in the tank 4 being free of agitation as a result of tank movement will readily permit the suspended matter to settle by gravity to the bottom of the tank and be deposited along the bottom wall 19.

After all air has been exhausted from the tank 4 and the reserve tank 17, the water level will have risen to the outlet 20 from which it is conducted by means of a pipe 21 into the water storage space 21a in the tender where it may be reused by circulating it to and through the boiler as needed.

It will be noted that the bottom wall 19 of the settling tank to which the suspended matter eventually gravitates is also inclined in the direction of the top wall 14 although to a less degree than that of the top wall. The bottom wall terminates in a sump 22 into which the deposit may be collected and removed.

In order to facilitate removal of deposits from the bottom wall 19, we have provided a plurality of pipes 23 arranged longitudinally of the settling tank 4 and spaced just above the wall 19. These pipes are connected at one end to a header pipe 24 through which water at high pressure may be admitted by opening a valve 25 in the high pressure line 26. The pipes 23 are provided with a plurality of perforations 27 opening in the direction of the wall 19. When water under high pressure is admitted to these pipes it will be ejected in a plurality of jets directed against the bottom wall 19 to loosen and flush out any deposit thereon. Since the wall 19 is inclined downwardly toward the sump 22, the flushed material will be conveyed to the sump.

A quick opening gate valve 28 is provided in the sump outlet to permit sludge from the sump to flow into a discharge pipe 29 which passes through the locomotive tender to discharge the sludge to the ground.

From the above description it will be readily understood that by our invention we have pro-

vided a simple apparatus by which suspended matter may readily and continuously be removed from steam boiler water without resorting to the use of baffles, filters, or the like, thus enabling the unladen water to be economically reclaimed for reuse in the boiler. Furthermore, we have provided a novel method of reclaiming boiler water for reuse.

Inasmuch as the settling tank 4 is disposed transversely of the tender, we have provided a walk way 30 overlying the tank 4 and having a hand rail 31 leading from one compartment of the tender to the other to enable the fireman or other persons to pass freely over the settling tank.

Various changes may be made in the details of construction and arrangement of parts without departing from the invention or the scope of the appended claim.

We claim:

An apparatus of the class described and adapted to be carried by a locomotive tender, said apparatus comprising a settling tank mounted transversely of a tender and in a position inclined to the horizontal, said tank having a steam boiler water inlet at the lower end of the inclined tank and outlets adjacent the other end of said tank, a reserve tank supported on said settling tank and overlying the outlets therein, said reserve tank having openings in register with the outlet openings of said settling tank whereby to exhaust air from said settling tank and to communicate boiler water from the top of the settling tank into said reserve tank, the bottom inclined wall of the settling tank terminating short of the inlet end of said tank, a header pipe having communication with a source of fluid under pressure extending transversely within the settling tank near its outlet end, and a plurality of conduits extending from said header and disposed along the bottom wall of the settling tank, said conduits having orifices opening toward said bottom wall whereby to subject a deposit of settled particles on said wall to dislodgment and movement along said wall when fluid under pressure is admitted to said header and conduits.
